(57) **CLAIM**

The ornamental design for an integrated spike and syringe, as shown and described.

DESCRIPTION

FIG. 1 is a perspective view of an integrated spike and syringe showing my new design.

FIG. 2 is a side view thereof, the opposite side being a mirror image.

FIG. 3 is a top view thereof, the bottom being a mirror image.

FIG. 4 is a front view thereof; and,

FIG. 5 is an enlarged view of the FIG. 4 tip.

The broken-line showing of environmental structure in FIGS. 1 through 4 is for illustrative purposes only and forms no part of the claimed design.
